UNITED STATES PATENT OFFICE.

WILLIAM J. KEENE, OF CHICAGO, ILLINOIS, ASSIGNOR TO CHICAGO SPRING BUTT COMPANY, OF CHICAGO, ILLINOIS, A CORPORATION.

SPRING-HINGE.

1,282,588.

Specification of Letters Patent. Patented Oct. 22, 1918.

Application filed June 2, 1917. Serial No. 172,402.

To all whom it may concern:

Be it known that I, WILLIAM J. KEENE, a citizen of the United States, and a resident of Chicago, county of Cook, and State 5 of Illinois, have invented certain new and useful Improvements in Spring-Hinges, of which the following is a specification.

The invention relates to spring hinges for the seats of toilet closets or hoppers and 10 seeks to provide an improved construction which will hold the seat yieldingly in raised position. A further object of the invention is to provide a spring hinge of this type with means for limiting the upward swing- 15 ing movement of the seat.

The invention consists in the features of improvement hereinafter set forth, illustrated in the preferred form in the accompanying drawings and more particularly 20 pointed out in the appended claims.

In the drawings, Figure 1 is a partial side elevation of a closet bowl and seat with the improved spring hinge applied thereto. Fig. 2 is a front view of the same, parts of 25 the bowl being shown in section on the line 2-2 of Fig. 1. Fig. 3 is a vertical rear elevation of the improved hinge. Fig. 4 is an enlarged plan view with the hinge structure shown in section. Figs. 5 and 6 are 30 cross sections on the lines 5-5 and 6-6 of Fig. 4. Fig. 7 is a view similar to Fig. 5 illustrating a modification.

The members of the improved hinge, which are secured respectively to the closet 35 bowl A and the seat B, are provided with overlapping end portions preferably in the form of pairs of ears 10 and 11 through which extends a connecting hinge pintle 12.

The hinge member having the ears 10 is 40 also provided with a transverse portion 13 which connects the lower rear side portions of the ears 10 and is preferably cast integral therewith. This hinge member is adapted to be secured to the upper rear portion 45 of the closet bowl and, for this purpose, is provided at its ends with integral seating flanges or feet 14 having rounded upper faces and horizontal lower faces which are arranged to engage the upper horizontal 50 face of the flange a of the bowl A. The seating portions 14 are also provided with integral depending bolts 15 which extend through openings provided therefor in the bowl flange, and nuts 16 and washers 17 55 upon the lower ends of the bolts, secure the

hinge structure in position. It should be noted that the lower faces of the seating portions 14 are below the overlapping ends and other parts of the hinge members so that the latter are properly supported in 60 position above the upper face of the closet bowl.

The other hinge member comprises a transverse portion 18 which connects the ears 11 and a seat-engaging flange 19, the 65 portion 18 and flange 19 being preferably cast integral with the ears 11. In the form shown in Figs 1 to 6 inclusive the seating flange is tangentially disposed with reference to the ears 11 and is adapted to extend 70 beneath and be secured to the lower face of the seat B by screws extending through openings formed therein. Preferably, this flange is of considerable extent and the rear edge of the seat is adapted to 75 abut against the portion 18 of the hinge member so that the seat is rigidly secured to the hinge structure.

In the construction shown, the ears 11 are 80 arranged outside of the ears 10 and the outer portions are in the form of truncated cones. One of the ears 11 is provided (see Fig. 4) with a seat for the conical head 20 of the hinge pintle and the other is provided with a threaded socket to receive the opposite 85 threaded end of the pintle.

The hinge members are provided with co-operating stop portions for arresting the upward swinging movement of the seat. For this purpose the rear portions of the ears 90 10 are enlarged or extended radially to form stops 21 having forwardly facing radial faces which are arranged to coöperate and engage the rear, radial edge face of the part 18 of the other hinge member. Preferably, 95 these stop portions are arranged to arrest the upward swinging movement of the seat with the latter inclined forwardly and upwardly as indicated most clearly in Fig. 1. The parts are held in the position shown 100 by a spring 22 coiled about the pintle 12 and connected at its ends respectively to the hinge members.

In the preferred construction shown, the 105 spring 22 is provided with inwardly projecting ends which detachably engage notches 23 formed in the inner ends of two collars 24 and 25. These collars are cylindrical and removably fit upon the pintle 12 and within cylindrical openings in the ears 10, with the ends 110

of the spring 22 engaging the notches 23 on the inwardly projecting ends of the collars. The collar 25 is provided with an enlarged outer end portion or flange 26 which is arranged between the ears 10 and 11 at one end of the hinge structure and is provided with a series of radial holes 27 for adjustably receiving a flanged stud 28. The outer projecting end of this stud is arranged to engage a seat formed in the adjacent edge of the part 18 of the seat-engaging hinge member. A stud 29 removably threaded into the other collar 24 is arranged to engage the adjacent edge of the part 13 of the other hinge member. In this way the spring is connected to the separate hinge members and normally holds the stop portions 18 and 21 in engagement with the seat raised and preferably upwardly and forwardly inclined. The tension of the spring may be radially adjusted by placing the stud 28 in any one of the radial holes or seats 27.

A cylindrical barrel 30 is provided for inclosing the spring 22. This barrel is of a length sufficient to extend between the inner faces of the ears 10. The opposite ends of the barrel are formed by two washers 31 that snugly fit within counter-bored end portions of the body of the barrel and loosely fit upon the inner projecting ends of the collars 24 and 25. At one point, the barrel 30 is provided with an opening for the stud 29.

The improved structure may be readily taken apart for repairs and the like without detaching the hinge members either from the closet seat or bowl. Thus, by removing the studs 28 and 29 and the hinge pintle 12—the headed end of the latter is slotted to receive a screw driver—the seat and seat-engaging hinge member can be removed. The collars 24 and 25 can be moved outwardly through the ears 10 and thus disengaged from the ends of the spring and spring barrel. The latter can then be slipped laterally from between the ears 10. Thus, the hinge structure, while extremely strong and rigid, can be readily taken apart for repairs, renewals or the like.

The construction shown in Fig. 7 is similar to that shown in Figs. 1 to 5 except that instead of having a seat-engaging flange which is substantially radial with respect to the axis of the hinge, it is provided with a seat-engaging flange 32 which extends in a circumferential direction with reference to the hinge axis, and, together with a flange or stop portion 33 that projects toward the hinge axis, forms the main body of the seat-engaging hinge member. The seat-engaging flange 32 abuts against the rear edge face of the seat B' and is preferably secured thereto by a pair of attaching bolts 34 fixed within the body of the seat and projecting from the rear edge thereof. Nuts 35 threaded on the bolts are disposed beneath the

flange or portion 33 and engage the outer face of the flange or portion 32 and rigidly connect the seat to the hinge member. In this form, the flanges 32 and 33 are connected to the ears 11 by the integral end portions 36 and the stud 28 engages a lug 37 formed upon the hinge member at one end. 70

It is obvious that changes may be made in the details set forth without departure from the essentials of the invention as defined in 75 the claims.

I claim as my invention:—

1. The combination with a closet bowl and seat therefor, of hinge members having overlapping end portions, a hinge pintle extending through said end portions, said hinge members having cooperating stop shoulders arranged adjacent and substantially radial with respect to said hinge pintle, one of said hinge members being secured 85 to said seat and adapted to hold the latter substantially in line with said hinge pintle, the other of said hinge members being secured to said bowl and having seating portions for holding said hinge members above 90 the face of the bowl, and a spring coiled about said hinge pintle and arranged to hold the seat in raised position with said radial stop shoulders in engagement, substantially as described. 95

2. A spring hinge for closet seats comprising two hinge members, one at least of said hinge members having a pair of spaced ears, a spring barrel arranged between said ears, a pintle for connecting said hinge members extending through said barrel and said ears, said hinge members having cooperating stop portions at their opposite ends arranged adjacent the periphery of said spring barrel, means for securing said hinge members to the closet bowl and seat respectively with the axis of the hinge above the upper face of the bowl and substantially in line with the seat, and a spring held about said hinge pintle within said spring 100 barrel and arranged to hold the seat in raised position with said stop portions in engagement, substantially as described. 105

3. In a spring hinge for closet seats, two hinge members each comprising a pair of spaced ears and a rigid transverse portion connecting said ears, a hinge pintle extending through said pairs of ears, the pair of ears of one member having projecting stop shoulders at the peripheral portions thereof 115 arranged to engage the transverse connecting portion of the other of said hinge members, means for securing said hinge members to the closet bowl and seat respectively with the axis of the hinge above the upper 120 face of the bowl and substantially in line with the seat, and a spring coiled about said pintle for holding said seat in raised position with the transverse connecting portion of one member in engagement with the stop 125 130

shoulders of the other member, substantially as described.

4. In a spring hinge for closet seats, two hinge members each comprising a pair of spaced ears and an integral transverse connecting portion between said ears, a hinge pintle extending through said pairs of ears, the pair of ears of one member having radial stop shoulders at the peripheral portions thereof arranged to engage the transverse connecting portion of the other hinge member, means for securing said hinge members to the closet bowl and seat respectively with the axis of the hinge above the upper face of the bowl and substantially in line with the seat; a spring coiled about said hinge pintle for holding the seat in raised position with the stop portions of said hinge members in engagement, a barrel inclosing said hinge and arranged between one of said pairs of spaced ears, and means on said pintle for holding said spring and barrel in position.

5. The combination with a closet bowl and seat therefor, of a hinge member comprising a pair of spaced ears having stop shoulders at their peripheries and seating portions and fastening devices for holding the same in position on said bowl, a second hinge member comprising a pair of spaced ears and an integral transverse connecting portion extending between the ears thereof and arranged to engage the stop shoulders of the other pair of ears, fastener bolts arranged substantially radial with respect to the axis of the hinge for securing said transverse connecting portion to the rear edge of said seat, a hinge pintle extending through said pairs of ears, a spring coiled about said pintle for holding said seat in raised position with said transverse connecting portion in engagement with said stop shoulders, a barrel inclosing said spring, and means on said pintle for removably holding said spring and said barrel in position, substantially as described.

6. In a spring hinge for closet seats, two hinge members each comprising a pair of spaced ears and an integral transverse portion connecting said ears, a hinge pintle extending through said pairs of ears, fastener bolts arranged substantially radial with re-

spect to the axis of the hinge for securing said hinge members to the closet bowl and seat respectively with the axis of the hinge 55 above the upper face of the bowl and substantially in line with the seat, collars mounted on said hinge pintle and each extending through one of said ears, a spring coiled about said hinge pintle and having 60 its ends engaging said collars, a barrel inclosing said spring and mounted on its ends on said collars, and studs projecting from said collars and engaging said hinge members respectively, substantially as described. 65

7. A spring hinge for closet seats and the like, comprising two hinge members having attaching means and pairs of spaced ears, a hinge pintle extending through said ears, collars mounted on said pintle, studs removable from the exterior of the hinge structure for connecting said collars to said hinge members respectively, one of said collars having a number of seats for its co-operating stud, a spring coiled about said 70 pintle and engaging said collars and a barrel mounted on said collars and inclosing said spring.

8. In a spring hinge for closet seats and the like, a hinge member having two ears, 20 a second hinge member having end portions arranged outside of said ears, a pintle extending through said end portions and said ears, a pair of collars mounted in said ears and removable from the outer sides thereof, a spring barrel mounted on said collars between said ears, a spring in said barrel coiled about said pintle and detachably engaging said collars at its ends, and devices for detachably connecting said collars to 85 said hinge members respectively.

9. In a spring hinge for closet seats, two hinge members, one of said members comprising two ears and a connecting portion between said ears, a coiled spring and an 95 inclosing barrel therefor extending between said ears, collars inserted through said ears and detachably engaging the ends of said spring and barrel for holding the same in position, a hinge pintle extending through 100 said collars, and means for connecting said collars to said hinge members respectively.

WILLIAM J. KEENE.
